G. G. TOWNSEND,
LEVELING INSTRUMENT,
APPLICATION FILED MAY 3, 1921. RENEWED JUNE 29, 1922.

1,437,327.

Patented Nov. 28, 1922.

UNITED STATES PATENT OFFICE.

GEORGE GALE TOWNSEND, OF FROSTBURG, MARYLAND.

LEVELING INSTRUMENT.

Application filed May 3, 1921, Serial No. 466,387. Renewed June 29, 1922. Serial No. 571,765.

To all whom it may concern:

Be it known that I, GEORGE GALE TOWNSEND, a citizen of the United States, and a resident of Frostburg, in the county of Allegany, and State of Maryland, have invented certain new and useful Improvements in Leveling Instruments, of which the following is a specification.

The present invention relates in general to surveying instruments, and more particularly to an improved leveling instrument of the type forming the subject-matter of my prior Patent No. 754,723.

The object of the invention is to provide a leveling instrument of this character which is simple and durable in construction, reliable and accurate in operation, easily and readily adjusted and controlled, and comparatively inexpensive to manufacture; which is not impaired by variations in temperature, or humidity or other physical changes in the environment in which it is used; which may be advantageously utilized in poor light or with artificial illumination, such as is used in mining work; which has its sight tube so mounted as to be readily disassembled to provide for convenient shipment; and which has its movable parts constrained to partake of movement within proper limits and susceptible of being locked in position when being transported.

Other objects and advantages of the invention reside in certain novel features of construction, combination and arrangement of parts which will be hereinafter more fully described and particularly pointed out in the appended claims, reference being had to the accompanying drawings forming part of this specification, and in which:

Figure 1 is an elevational view of the invention, the staff being broken away;

Figure 2 is a similar view in longitudinal section;

Figure 3 is a top plan view thereof;

Figure 4 is an elevational view of one end of the sight tube;

Figure 5 is a fragmentary view in horizontal section of the sight tube;

Figure 6 is a detail view in section of the friction stops for the latch; and

Figure 7 is an elevational view of the complete instrument.

Referring to the drawings wherein for the sake of illustration is shown the preferred

embodiment of the invention, the numeral 10 designates a supporting staff provided with a slot 11 adjacent to the upper end thereof and having a head 12 at the upper end and extending across the slot. The head 12 and the staff are of one piece and preferably are constructed of wood. Metallic side plates 13 are suitably secured, as by screws 14, to the side faces of the staff adjacent the upper end thereof and extend across the side faces of the head 12. Metallic reinforcing plates 15 and 16 are inset in suitable saw cuts provided therefor in the head 12 and extend at right angles to the side plates 13 and abut these side plates at their ends, the plates 15 and 16 being arranged in spaced and parallel relation with respect to each other. Suitable fastening means is provided for maintaining the plates in position and preferably consists of a plurality of nails or pins 17 driven through the head and extending through suitable openings drilled in the metallic plates 15 and 16. The head 12 is severed transversely and a filling F of elastic material such as bees wax and rosin or similar substance is arranged between the severed portions of the head.

A spindle 18 is rotatably mounted within the staff by means of trunnions 19 carried thereby and rotatably journaled in the side plates 13. A sight tube support designated 20 generally at 20, is mounted upon the spindle 18. This sight tube support comprises a metallic frame which may be cast or wrought as desired and which if wrought, includes overlapping sections 21 and 22 having aligned openings 23 receiving the spindle 18 and having a seat 24 adapted to receive the sight tube. The frame also includes a depending portion 25 having a pivot bearing 26 therein for a purpose which will hereinafter more fully appear.

A sight tube 30 is mounted in the seat 24 of the sight tube support and is retained in position therein by means of a set screw 31 threaded through the sections 21 and 22 of the frame and extending through a transverse opening of the spindle and having its pointed end 31^a engaging the outer wall of the sight tube. The head 12 is provided above the set screw 31 with an opening 12^a affording access to the slot of the screw whereby it may be manipulated by a screw driver or other suitable instrument. By

thus mounting the sight tube 30 it is obvious that while it is properly and securely supported in position when the set screw is turned home nevertheless it may be readily 5 disassembled to provide for convenient shipment of the instrument by merely loosening the screw 31 and withdrawing the sight tube from its seat 24. It is to be noted that the set screw 31 also serves to lock or secure the 10 frame to the spindle.

A sighting device, designated generally at 34, is arranged within and near one end of the sight tube, and a coaxing sighting device, designated generally at 35, is arranged 15 within and near the other end of the sight tube and is oppositely arranged with respect to the first-named sighting device. Both of the sighting devices are of identical construction, though oppositely arranged 20 and each includes a flat ring 36 which engages the inner wall of the sight tube 30, and is suitably secured thereto, an opaque semi-circular diaphragm 37 carried by the flat ring 36 and having a peep-hole 38 there- 25 in and a cross wire 39 which extends horizontally of the sighting device and has one end secured to the ring 36, as at 40, and the other end secured to the semi-circular dia- phragm, as at 41. At the intersection of 30 the cross wire and the vertical line pre- sented by the edge of the diaphragm there is provided a V-shaped notch 42, the apex of which lies on the cross wire.

A weight 50 constituting a pendulum is 35 fixed to the lower end of the rod 51, which in turn is mounted upon the pivot bearing 26 of the sight tube support by means of a pivot pin 52. An adjusting screw 53 is carried by a threaded bearing 54 pro- 40 vided therefor in the frame and abuts at its inner end a reduced and flattened portion 51^a provided at the upper end of the rod 51 and this adjusting screw together with an opposing spring 55 con- 45 stitutes a means whereby the pendulum may be adjusted when necessary. It is to be noted that the pendulum 50 is freely suspended upon the side plates 13 by means of the frame, trunnions and spindle, and 50 that the pendulum thereby controls the sight tube support and consequently the sight tube itself.

Means is provided for locking the pen- 55 dum in position against vibration and preferably includes a pivoted latch bar 56 carried by the staff and operating in an extension 11^a of the slot 11 and having a lock lug 57 adapted to be received in a re- 60 cess or seat 58 provided in the under side of the pendulum. The latch bar is pro- 65 vided with an operating knob 59 whereby it may be readily manipulated. A transverse opening 56^a is formed in the latch bar and receives a telescoping barrel 60 having a friction head 62 which is engageable with

the adjacent side of the slot and is urged into frictional engagement therewith by means of a coil spring 64 disposed in the barrel and urging the friction head out- 70 wardly and against the wall of the slot. The latch bar is thus maintained in any position to which it may be adjusted but it is not absolutely held against movement for the operator may easily apply a suf- 75 ficient force to the latch bar to move its lock lug 57 into and out of engagement with the recess of the pendulum 58.

Stop lugs 65 are carried by the pendu- 80 lum and coact with the lock lug 57 when the latch bar is in open position to limit the amplitude of the vibration or the swing of the pendulum, thus preventing excessive swing and consequent injury or distortion of the parts. A wind guard 66 may be pro- 85 vided if desired.

In use, the staff is grasped below the weight and held in approximately vertical position. The sight tube under the influence of the pendulum will then instantly assume a horizontal position and the sight 90 can then readily be taken. Under ordinary conditions sight is taken through the peep- 95 hole 38 and on the cross wire 39 but it may be taken by means of the peep-hole and one of the notches 42 and when the light is bad this is preferred as these are operable for sighting purposes even in very poor light or when artificial illumination is made use of. The staff can be easily turned to present one or the other ends of the sight tube to the eye to take the sight or effect 100 adjustment. It is to be noted that adjustment may be readily made by manipulat- 105 ing the adjusting screw 53.

The trunnions and side plates provide a delicate yet strong suspension for the pen- 110 dum and this suspension is not impaired by variations in the temperature as the construction of the head precludes move- 115 ment of the side plates toward and away from each other and particularly toward each other which latter movement would be liable to bind the suspension and preclude easy operation.

The latch bar and its lock lug provide 115 ready means for locking the pendulum against vibration when it is being trans- ported, and this together with the demount- 120 able sight tube provide an instrument of this character which may be readily packed for shipment.

As shown in Figure 7, the staff 10 may, if desired, consist of sections detachably se- 125 cured together with a construction of this character the height of the staff may be varied and thus the staff may be adapted to various uses and particularly it may be adapted for use in low workings in mines.

I claim:

1. In a leveling instrument, a staff hav- 130

- ing a slot therein adjacent the upper end thereof, a head at the upper end of the staff, side plates secured to the staff and to the head, metallic reinforcing plates inset in the 5 head and abutting the side plates, said head being severed transversely, a filling of elastic material between said severed portions, a spindle having trunnions rotatably journaled in said side plates, a sight tube sup- 10 port comprising a frame carried by said spindle and having a seat adapted to receive a sight tube and a depending extension, a sight tube arranged in the seat of said frame, sighting devices in said sight tube, common means for securing the frame to the spindle and for securing the sight tube in its seat, a pendulum, a rod carrying the pendulum at its lower end, means for pivotally mounting the rod upon the ex- 15 tension of the frame, an adjusting screw 20 engaging the upper end of the rod, an opposing spring for said adjusting screw, a latch bar pivoted to the staff and having a lock lug, said pendulum having a recess 25 adapted to receive said lock lug, means carried by the latch bar for maintaining it in adjusted position, and stop lugs carried by the pendulum and cooperable with the lock lug to limit the movement of the pendulum. 30 2. In a leveling instrument, a staff having a slot therein, a spindle, a sight tube support comprising a frame carried by said spindle and having a seat adapted to receive a sight tube and a depending extension, a sight tube arranged in the seat of said frame, sighting devices in said sight tube, common means for securing the frame to the spindle and for securing the sight tube in its seat, a pendulum, a rod carrying the 35 pendulum at its lower end, and means for pivotally mounting the rod within the ex- 40 tension of the frame, an adjusting screw engaging the upper end of the rod, an opposing spring for said adjusting screw, a latch bar pivoted to the staff and having a lock lug, said pendulum having a recess adapted to receive said lock lug, means carried by the latch bar for maintaining it in adjusted 45 position, and stop lugs carried by the pen- 50 dum and cooperable with the lock lug to limit the movement of the pendulum. 3. In a leveling instrument, a staff having a slot therein adjacent the upper end thereof, a head at the upper end of the staff, side plates secured to the staff and to the head, metallic reinforcing plates inset in the 55 head and abutting the side plates, said head being severed transversely, a filling of elastic material between said severed portions, a spindle having trunnions rotatably journaled in said side plates, a sight tube sup- 60 port comprising a frame carried by said spindle and having a seat adapted to receive a sight tube and a depending extension, a sight tube arranged in the seat of 65
- said frame, sighting devices in said sight tube, common means for securing the frame to the spindle and for securing the sight tube in its seat, a pendulum, a rod carrying the pendulum at its lower end, and means for pivotally mounting the rod upon the ex- 70 tension of the frame. 4. In a leveling instrument, a staff having a slot therein adjacent the upper end thereof, a head at the upper end of the staff, side plates secured to the staff and to the head, metallic reinforcing plates inset in the head and abutting the side plates, said head being severed transversely, a filling of elastic material between said severed portions, a spindle rotatably journaled in said side plates, a sight tube support carried by the spindle, a sight tube carried on said support, and a pendulum controlling said sight tube support. 85 5. In a leveling instrument, a staff having a slot therein, a spindle rotatably journaled on said staff, a frame carried by said spindle and having a seat, a sight tube supported on the seat of said frame and common means for securing the frame to the spindle and for securing the sight tube in its seat. 90 6. In a leveling instrument, a staff, a sight tube support pivotally mounted in said staff, a sight tube carried by said sight tube support, a pendulum controlling said sight tube support, a latch bar pivoted to the staff and having a lock lug, said pendulum having a recess adapted to receive said lock lug, means carried by the latch bar for maintaining it in adjusted position, and stop lugs carried by the pendulum and cooperable with the lock lug to limit the movement of the pendulum. 95 7. In a leveling instrument, a staff, a sight tube support pivotally mounted on said staff, a sight tube carried by said sight tube support, a pendulum controlling said sight tube support, a latch bar pivoted to the staff and having a lock lug, said pendulum having a recess adapted to receive said lock lug and means carried by the latch bar for maintaining it in adjusted position. 105 8. In a leveling instrument, a staff, a sight tube support suspended within said staff, a sight tube carried by said sight tube support, a similar sighting device arranged near each end of said sight tube and including a flat ring, an opaque semi-circular diaphragm having a peep-hole therein, and a cross wire secured at one end to said ring and at the other end to said diaphragm, said diaphragm having a V-shaped notch therein having its apex coincident with said cross wire. 115 9. In a leveling instrument, a sighting device including a flat ring, an opaque semi-circular diaphragm having a peep-hole therein and a cross wire secured at one end to said ring and at the other end to said dia- 120 125 130

phragm, said diaphragm having a V-shaped notch therein having its apex coincident with said cross wire.

10. A leveling instrument, a staff having a head and having a slot therein, adjacent the upper end thereof, side plates secured to the staff and to the head, metallic reinforcing plates carried by said head, said

head being severed transversely, a filling of elastic material between said severed portions, a spindle rotatably journaled in said side plates, a sight tube support carried by the spindle, a sight tube carried on said support and a pendulum controlling said sight tube support.

GEORGE GALE TOWNSEND.
